Primary Examiner—Nelson C. Holtje

(74) Attorney, Agent, or Firm—Banner & Witcoff, Ltd.

(57) **CLAIM**

The ornamental design for a portion of a watch, as shown and described.

DESCRIPTION

FIG. 1 is a perspective view of a portion of a watch showing my new design;

FIG. 2 is a top plan view thereof;

FIG. 3 is a side view of one side thereof, the other side being a mirror image thereof;

FIG. 4 is an end view thereof, the other end view being a mirror image thereof; and,

FIG. 5 is a bottom view thereof.

The broken line showing of the end portions of the watch band is for illustrative purposes only and forms no part of the claimed design.
